United States Patent [19]

Hara et al.

[11] Patent Number: Des. 306,579

[45] Date of Patent: ** Mar. 13, 1990

[54] OPTICAL DISK UNIT FOR ELECTRONIC COMPUTERS

[75] Inventors: Kunio Hara, Chiba; Atsushi Tani, Yokohama, both of Japan

[73] Assignee: Kabushiki Kaisha Toshiba, Kawasaki, Japan

[**] Term: 14 Years

[21] Appl. No.: 180,261

[22] Filed: Apr. 7, 1988

[30] Foreign Application Priority Data

Oct. 9, 1987 [JP] Japan 62-41115

[52] U.S. Cl. D14/109

[57] CLAIM

The ornamental design for an optical disk unit for electronic computers, as shown.

DESCRIPTION

FIG. 1 is a top, front and right side perspective view of an optical disk unit for electronic computers showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.

FIG. 1

FIG. 2

FIG. 3

FIG. 4

FIG. 5

FIG. 6

FIG. 7
